UNITED STATES PATENT OFFICE.

HENRY WALTER SWITZER, OF HAMILTON, ONTARIO, CANADA, ASSIGNOR TO WILLIAM H. HEIMBACH, OF BUFFALO, NEW YORK.

WINDOW.

Application filed August 15, 1924, Serial No. 732,291, and in Canada March 22, 1924.

This invention relates to improvements in windows and the objects of the invention are to provide an efficient and weather-proof window having counter-balanced sashes, pivotally mounted on carrying bars, whereby the window can be easily swung inwardly to be cleaned on both sides from within.

Further objects are to provide an improved window of this description, provided with means for locking the sashes when set at an angle for ventilation and swung inwardly for cleaning.

Further objects are to provide a window of this class in which suitable supporting means are included for the sashes, when swung inwardly.

Yet a further object is to provide a window of this character having in combination with the sills, the carrying bars and the sashes, an adjustably mounted weather strip, whereby the window is rendered absolutely wind-proof.

A still further object is the provision of a window, embodying the above and other improvements, that can be manufactured and placed on the market for practically the same price as the ordinary window without any improvements.

With the foregoing and other objects in view, the invention consists essentially in the novel construction and arrangement of parts, described in the present specification and illustrated in the accompanying drawings that form part of the same.

Referring now to the drawings in which like characters of reference indicate corresponding parts in each figure:

Figure 1 is a front elevation of an embodiment of my improved window, from the inner side, with sashes closed.

Figure 2 is a vertical section, with sashes closed.

Figure 3 is a vertical section with the lower sash raised and swung inwardly. The dotted lines indicate the inward position of the upper sash when swung inwardly.

Figure 4 is a cross section with window down.

Figure 5 is a sectional detail, showing the connection between the window sashes and the frame, with the weather strip.

Figure 6 is a perspective view of the carrying bar detached from the window.

Figure 7 is a sectional detail showing the reinforcing plate for the carrying bar.

Figure 8 is an enlarged section on line 8-8 of Figure 1.

Figure 9 is an enlarged fragmentary section through the adjustable weather strip.

Figure 10 is a perspective detail of the weather strip.

Figure 11 is a section on line 11-11 of Figure 3.

In the drawings A designates an embodiment of my improved window as a whole, comprising a rectangular frame, of any well known construction, formed of sides 10 and 11, top 12 and base or sill 13. Within this frame are mounted, as hereinafter more fully described, the top and bottom window sashes 14 and 15.

Referring now more particularly to Figures 2 and 3, it will be seen that the sashes 14 and 15 counter-balance one another and that they are pivotally mounted at their lower ends at 16 and 17 on carrying bars 18, these carrying bars being designed to travel upwardly and downwardly in channels 19 and 20 respectively, formed in the sides of the window frame and separated by a stop 21. These carrying bars 18 are connected to one another by means of a flexible cable or rope 22 secured at each end to hook members 23 in the top of said bars, the cable being designed to travel over a pulley 24 mounted in the extreme upper end of the stop member 21 and whereby the bars and the window sashes, pivotally carried thereby, are counter-balanced.

From the foregoing it will be seen the operation of the window, so far, will be self-evident; on the upper sash 14 being moved downwardly the lower sash 15 counter-balancing it will move upwardly and vice versa.

To provide draft-proof ventilation and also to lock the window in open position, I provide catches 25 on the inside of each sash, these catches being designed to engage with orifices 26 in the carrying bars 18. Furthermore to support the window sash, when swung inwardly for cleaning purposes, at any required angle, I provide supporting buffers 27, of any suitable material, in the sides of the frame, or if required in any other desired or more suitable place, for instance on the bottom or sill of the frame, these buffers being designed to support the window for cleaning it on both sides and for retaining the window at any angle required and without danger of its becoming discon-

nected with the carrying bars or otherwise injuring it.

Coming now to the wind-proof means for the window as a whole and which form an essential feature of my invention, I attain this, as here illustrated, by means of a substantially L-shaped weather strip 28 in combination with and adapted to fit into vertically extending grooves or slots 29 in each of the channels 19 and 20. The formation of this strip enables it to practically embrace the top and bottom of one side of the carrying bars and to slidably engage therewith. The opposite side of this strip to that engaging the groove 29 is designed to engage with a groove 30 in the window sash, thus forming a complete wind-proof means in combination with the frame and the window sash.

Another essential feature of my weather strip is that instead of being fixedly secured to the stop 21, it is adjustably or movably secured thereto, so that it can move inwardly and outwardly, this being arranged by having openings 31 through the strip and into which the securing means extend, of larger size than said securing means.

Another and further improvement in regard to this strip is that it may also be suitably secured on the carrying bar itself, while at the same time adapted to simultaneously engage with the groove 29 in the window frame, and the groove on the sash 30.

Referring now more particularly to the catches 25, on the inside of each sash, as illustrated more particularly in Figure 8, it will be noted that they are preferably provided with actuating springs 25' for the bolts or catches 25, adapted to engage with orifices 26 in the carrying bars. When it is desired to securely lock the windows in ventilating position the catches 25 are designed to engage with orifices in the carrying bars registering with orifices in the window frame so that any movement of the window sash is completely prevented.

The pivotal means by which at 16 the sashes are pivotally mounted on the carrying bars 18, consist of similar spring-actuated catch members to those already described and designated by the numeral 25 and are embedded in the base of each of the window sashes and designed to engage with each of a series of openings, plates protected in the carrying bars. 32 are reinforcing plates for the carrying bars.

As many changes could be made in the above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:

1. In a window and in combination a frame, stiles flexibly connected to one another and slidably mounted in the frame, a pair of counter-balanced sashes pivotally mounted on the stiles, buffers for regulating the pivotal travel of the sashes inwardly, grooves in the sashes and corresponding grooves in the frame and weather strips secured to the stiles and adapted to simultaneously engage with both grooves. 75

2. A window and in combination, a frame, upper and lower counter-balanced sashes slidably supported and pivotally mounted at their lower ends in said frame, buffers of resilient material secured on opposite sides of the frame adjacent the lower end thereof to automatically engage with the sashes on the sashes being swung inwardly to form therewith an axis whereby the sashes are automatically retained rigid at a required angle, a weather strip interfitting on one side with the frame and on the other side with said sashes respectively. 85

3. In a window of the character described, the combination with a frame, stiles slidably held in said frame, a sash pivotally hung at its lower end between said stiles, weather strips secured to the stiles and means formed in the frame and the sash permitting the weather strips to interfit on one side with the frame and on the other side with the sash respectively. 90

4. In a window of the character described, the combination with a frame, slidably mounted stiles in said frame, of a sash pivotally mounted on the stiles, buffers of resilient material in the frame adapted in co-operation with the pivotally mounted and slidably supported sash to form an axial or fulcrum point for the sash when swung inwardly to automatically retain it rigid at a required angle weather strip secured to the stiles and extending thereacross to interfit on one side with the frame and on the other side with the sash respectively. 100

5. A window and in combination, a frame, stiles slidably operable in said frame, flexible means connecting said stiles, upper and lower counter-balanced sashes pivotally mounted adjacent their lower ends on the stiles, sash engaging yieldable members secured on opposite sides of the frame to engage with the sashes to form therewith when swung inwardly a fulcrum point whereby the sashes are rigidly retained at a required angle, weather strip engaging means formed in the frame and sash, and weather strips secured to the stiles adapted to interfit on one side with the frame and on the other side with the sash respectively. 110

6. In a window of the character described, the combination with a frame, stiles slidably held in said frame and a sash pivotally hung between said stiles, of weather strips respectively interfitting on one side with 125

said frame and on the other with said sash, each weather strip extending across the corresponding stile.

7. In a window of the character described, the combination with a frame, stiles slidably held in said frame and a sash pivotally hung between said stiles, of weather strips re-

spectively secured to said stiles and extending thereacross so as to interfit on the one side with said frame and on the other side ¹⁰ with said sash.

In witness whereof I have hereunto set my hand.

HENRY WALTER SWITZER.
